HAIR CLIPPER

Wellington Arthur Sneed, Davenport, Iowa

Original application December 30, 1949, Serial No. 136,073, now Patent No. 2,603,865, dated July 22, 1952. Divided and this application May 2, 1952, Serial No. 285,616

5 Claims. (Cl. 30—233.5)

1

The present invention relates to hair cutting devices, particularly to hair clippers, and the like, and is a division of my application, Serial No. 136,073, filed December 30, 1949, now Patent No. 2,603,865, granted July 22, 1952.

The object and general nature of this invention is the provision of a hair cutting implement by which one may cut his own hair easily and conveniently, especially the hair at the back of the head and neck. More specifically, it is an important feature of this invention to provide a hair cutting device which is especially constructed to be held by one hand, with the fingers engaging the device at its upper portion when it is held back of the neck or head and with the thumb engaging and operating the cutting unit by an upward movement of the thumb, as by the simple act of contracting the hand when it holds the device back of the head, with the finger-receiving portions disposed upwardly.

Further objects of this invention are the provision of a hair cutting device having detachable and interchangeable comb units, so as to adapt the device for most convenient use with either thin or thick hair and for cutting hair of different lengths and/or under variable conditions of use; the provision of a hair cutting device comprising a fixed cutterbar and a swingable cutter blade pivotally associated therewith by means which facilitates adjustment of the pivot axis of the swingable element; and such further objects, advantages, and capabilities as will hereafter appear and as are inherent in the construction disclosed herein. My invention further resides in the combination, construction, and arrangement of parts illustrated in the accompanying drawings and, while I have shown therein what is now regarded as the preferred embodiment of this invention, I desire the same to be understood as illustrative only and not to be interpreted in a limiting sense.

In the drawings annexed hereto and forming a part hereof,

Fig. 1 is a side view of one form of my invention;

Fig. 2 is a bottom view taken along the plane indicated by the line 2—2, Fig. 1;

Fig. 3 is a top view taken along the plane indicated by the line 3—3, Fig. 1;

Fig. 4 is an end view taken substantially along

2

the plane indicated by the line 4—4, Fig. 1, with the swingable cutter blade in a position to begin its cutting stroke;

Fig. 5 is a similar view, showing the swingable cutter blade after starting its cutting stroke;

Fig. 6 is a sectional view taken along the plane indicated by the line 6—6, Fig. 4;

Fig. 7 is a detail view of one of the auxiliary comb guide units attachable to the frame of the device;

Fig. 8 is a side view of the comb guide member shown in Fig. 7;

Fig. 9 is an end view of the same comb guide member;

Fig. 10 to 12 are views similar to Figs. 7 to 9, showing another form of auxiliary comb guide;

Figs. 13 to 15 are detail views of the swingably mounted cutter blade; and

Fig. 16 is a sectional view showing the latching means for holding the auxiliary comb member in place.

Reference will now be made in greater detail to the annexed drawings for a more complete description of this invention. In Figs. 1 to 5, the hair cutting device of the present invention incorporates a frame 1 comprising an elongated member having at one end a finger hold section 2 provided with three finger holes 3 and at the other end with a forked section 4 having sides 5 and 6, the plane of the latter lying at right angles to the plane of the finger hold section 2. Fixed to the forked section 4 of the frame 1, between the sides 5 and 6 thereof, is a U-shaped part 9 which has sides 11 and 12 fixed to the sides 5 and 6. The central section 13 of the U-shaped part 9 carries a stationary cutterbar 14 which is secured in place by bolts 15, or other suitable means, and a toothed comb guide section 16 having a plurality of teeth 17 extending at an acute angle relative to the frame 1 and directed, in general, toward the finger hold section 2. The base or central portion 18 of the comb guide part has grooves 19 aligned with the spaces between the teeth 17, as best shown in Fig. 2.

The sides 11 and 12 are slotted to receive a pivot shaft 23 upon which a rockable cutter unit 24 is swingably mounted. The unit 24 comprises a U-shaped part 25 having sides 26 and 27 apertured to receive the pivot shaft 23. One end of the shaft 23 is carried in a shiftable bearing 28,

the position of which relative to the frame 1 is adjusted by a screw-threaded member 29 carried in lugs 30 on the side 12, as best shown in Figs. 3 and 5. The other end of the pivot shaft 23 is pressed toward the cutterbar 14 by a spring-biased plunger 33 connected to the shaft 23 and acted upon by a spring 34 disposed in a casing 35 which is fixed to the side 11. Adjustment of the spring 34 is effected by a screw-threaded member 36 at the outer end of the spring casing 35.

The rockable cutter unit 24 has at its central portion an extension 38 which is approximately a segment of a cylinder and upon which a cutter blade 39, in an angled position, is fixed, as by screws 41 and a clamp bar 42 which the screws 41 fasten to the extension 38. A thumb-receiving socket 43 is formed on the member 24 by a thumb-strap 44, attached in any suitable manner to the central section of the U-shaped member 25. The swingable member 24 is biased for movement to the position shown in Figs. 1 and 6 by a torsion spring 47 encircling the shaft 23 and having one end 48 fixed to the stationary frame side 11; and the other end 49 is fixed to the side 27 of the rockable cutter unit 24. A sleeve 51 extends around the spring 47.

The comb guide teeth 17 are primarily designed for use with short hair, as at the back of the neck. For use where the hair is thicker, I provide a pair of auxiliary comb guide units 60 and 70. Referring first to the unit 60, shown in Figs. 10 to 12, the unit comprises a base member 61 having a plurality of grooves 62 and a plurality of openings 63 in which the teeth 64 are fixed. A curved pin 65 is secured to each end of the bar 61 and they are adapted to be detachably received in a pair of openings 66 in the end portions of the U-shaped frame part 9, and held therein by any suitable holding means, comprising a lever 67 pivoted at 68 to the side 11, actuated into holding position by a spring 69 and provided with a holding nose 67a engaging the notches in the pins 65 or 73. The pins 65 may be ridged or serrated, if desired. The unit 60 is shaped so that the teeth 64 lie below the teeth 17.

The auxiliary comb guide unit 70 is substantially like the unit 60 except that the teeth 71 are longer than the teeth 64. The base 72 is dimensionally similar to the base 61 and the attaching pins 73 are adapted to be mounted in the openings 66, the same as the pins 65.

The operation of this device is as follows. The user places first, second, and third fingers in the openings 3 at the end of the frame 1, and then places his thumb in the thumb socket 43. This enables the user to firmly hold the device. Held in this fashion, when the user brings his hand back of his head in a natural position, regardless of whether the device is held in the left hand or in the right hand, the finger hold end 2 is uppermost and the comb guide 16 is in a lowermost position with the teeth 17 extending upwardly. Then, by bringing the device close to the head, the teeth 17 will engage the hair and movement of the thumb toward the fingers, which is a natural grasping movement, will act to swing the rockable cutter blade 39 to swing downwardly across the stationary blade 14 in hair-cutting relation. The blade 39 engages the cutterbar 14 at an angle, as best shown in Fig. 5, and the end of the blade 39 which first engages the cutterbar 14 is rounded, as indicated at 55 in Fig. 13. The relation between the end 55 of the blade 39 and the stationary cutterbar or blade 14 is con-

trolled by shaft adjustment 28, 29, 36, described above. The other portions of the blade 39, as it moves across the fixed blade 14, are pressed against the latter by the spring 34 and associated parts, thereby assuring positive cutting or shearing action.

It is of course understood that the specific description of structure set forth above may be departed from without departing from the spirit of my invention as disclosed herein and as defined in the appended claims.

Having now described my invention, I claim:

1. A hair cutting device particularly adapted for self use, comprising a frame having a finger-hold section at one end and a toothed comb guide fixed to the other end and extending at an acute angle with respect to the frame, a fixed cutter blade at the base portion of said toothed comb guide, a thumb-actuated part carried at said other end of the frame and including a thumb-receiving section movable toward said finger-hold section, and an oscillatable blade movable across said fixed cutter blade in a direction away from said finger hold section.

2. A hair cutting device comprising a frame and a handle, having one portion adapted to receive the fingers of one hand of the user, in combination with a comb member fixed to said frame and making an acute angle with respect to said handle, a rotatable part oscillatably connected with the part of said frame opposite the comb member and including a thumb-receiving actuator movable toward and away from said finger-receiving frame portion, and a relatively fixed cutter blade carried by the frame adjacent the base of said comb member, a movable cutter blade carried by said oscillatable part in a position thereon to move therewith in hair cutting relation across said fixed blade when said thumb-receiving actuator is shifted toward the first mentioned frame portion, and spring means connected between said frame and said oscillatable part for shifting the latter in the other direction when the thumb pressure exerted thereagainst is relaxed.

3. A hair cutting device comprising a frame having one portion adapted to receive the fingers of one hand of the user, a comb fixed to said frame, a part oscillatably connected with the opposite portion of said frame and including a thumb-receiving actuator movable toward and away from said finger-receiving frame portion, a relatively fixed cutter blade carried by the frame adjacent the base of said comb, and a movable cutter blade carried by said oscillatable part in a position thereon to move in hair-cutting relation across said fixed blade when said thumb-receiving actuator is shifted toward said first frame portion.

4. A hair cutting device comprising a frame having a finger hold section at one end, a comb guide member at the other end of said frame and extending divergently toward said finger hold section, hair cutting means adjacent said guide member, and a thumb-receiving part pivoted to said frame adjacent to and operatively connected with said cutting means for actuating the latter when said thumb-receiving part is oscillated toward said finger hold section.

5. A hair cutting device comprising a frame having a finger-hold section at one end, a comb-guide member at the other end of said frame and extending divergently toward said finger-hold section, a comb provided with curved pins for insertion in the frame part, hair-cutting means adjacent said guide member, and a thumb-receiving

part pivoted to said frame adjacent to and operatively connected with said hair-cutting means for actuating the latter when said thumb-receiving part is oscillated toward said finger-hold section.

WELLINGTON ARTHUR SNEED.
